UNITED STATES PATENT OFFICE

153,246

DESIGN FOR AN EMBROIDERED LACE

Jack Wiener, New York, N. Y.

Application December 6, 1947, Serial No. 143,011

Term of patent 3½ years

(Cl. D47—6)

To all whom it may concern:

Be it known that I, Jack Wiener, a citizen of the United States, residing in the Borough of Manhattan, city, county, and State of New York, have invented a new, original, and ornamental Design for an Embroidered Lace, of which the following is a specification, reference being had to the accompanying drawing, forming a part thereof, in which the figure in the drawing is a face view of a piece of an embroidered lace, embodying my new design.

The embroidered lace is shown against a black background to bring out the details of the design.

I claim:

The ornamental design for an embroidered lace, as shown and described.

JACK WIENER.
